UNITED STATES PATENT OFFICE.

CHARLES S. SHARP, OF AUBURN, NEW YORK, ASSIGNOR TO D. M. OSBORNE AND COMPANY, OF AUBURN, NEW YORK, A CORPORATION OF NEW YORK.

RIDING SPRING-TOOTH HARROW.

SPECIFICATION forming part of Letters Patent No. 781,100, dated January 31, 1905.

Application filed October 8, 1904. Serial No. 227,720.

To all whom it may concern:

Be it known that I, CHARLES S. SHARP, a citizen of the United States, residing at Auburn, in the county of Cayuga and State of New York, have invented certain new and useful Improvements in Riding Spring - Tooth Harrows, of which the following is a specification.

In harrows of this class where rocking tooth-bars are used and the wheels of the sulky are located within the frame it is usually the case that the tooth-bars when rocked will come in contact with the wheels; and the object of my invention is to overcome this defect in a simple and effective manner, as will be hereinafter shown.

The sulky used is more fully described in my application filed December 21, 1897, Serial No. 662,802.

Referring to the drawings, Figure 1 is a plan view of my improved riding-harrow, and Fig. 2 is a longitudinal section on the line X X of Fig. 1.

My improved harrow is composed of two sections hinged together, the metallic frames A being bent so as to form side and front bars. Rocking tooth-bars B, their ends bent at right angles, are pivoted to the side bars of the harrow-frames at a. Each tooth-bar B has spring harrow-teeth secured to it in any suitable manner. Midway between the side bars of each harrow-section are bars C, secured to the front of the frames A A'. Standards b are secured to and project upwardly from the tooth-bars B and are pivoted to the central bars C at b'. The upper ends of the standards b are pivoted to horizontal bars a', which are parallel with the bars C. Set-levers of the usual construction are rigidly attached to the rear standards and provided with locking-dogs, which engage with the teeth of quadrants b² on the bars a'. Shoes D are pivotally attached to the front of the harrow-frames A A'.

Secured to the front tooth-bars are rearwardly-projecting brackets d, to which are pivotally connected bars d', rigidly attached at their rear ends to the sulky or riding part of the harrow. The sulky straddles the inner frame-bars of the harrow, the wheels being

located between the rear tooth-bars and approximately equidistant therefrom.

When the tooth-bars B are rocked to raise the harrow-teeth out of engagement with the ground, it is obvious that their movement would be limited by the tooth-bars immediately in front of the wheels coming in contact with the latter. By pivotally attaching the bars d' to the rear of the front tooth-bars, preferably to a bracket secured to the tooth-bars and projecting rearwardly, when the tooth-bars are rocked the sulky is moved to the rear at the same time, as shown in dotted lines, Fig. 2, and drawn forward again by the same means when the tooth-bars are rocked downwardly to bring the harrow-teeth into an operative position, so that whatever the movement of the tooth-bars the wheels of the sulky are always in the same relative position.

Having thus described my invention, what I claim, and desire to cover by Letters Patent, is—

1. A rocking-tooth-bar harrow, in combination with a sulky therefor, and means connecting the harrow and the sulky to move the latter when the tooth-bars are rocked.

2. A rocking-tooth-bar harrow, in combination with a sulky within the harrow, and means connecting the harrow and the sulky to move the latter when the tooth-bars are rocked.

3. A rocking-tooth-bar harrow, in combination with a sulky within the harrow, and means connecting the harrow and the sulky to move the latter coincidently with the movement of the tooth-bars.

4. A rocking-tooth-bar harrow, in combination with a sulky within the harrow, and means connecting the sulky with the forward tooth-bars of the harrow to move the sulky when the tooth-bars are rocked.

5. The combination with a rocking-tooth-bar harrow, of a sulky within the harrow, having wheels between the rear tooth-bars, and means connecting the harrow and the sulky to maintain the relative position of the wheels and the rear tooth-bars when the tooth-bars are rocked.

6. The combination with a rocking-tooth-bar harrow, of a sulky within the harrow, hav-

ing wheels between the rear tooth-bars of the harrow and approximately equidistant therefrom, and means connecting the harrow and the sulky to maintain the relative position of 5 the wheels and the rear tooth-bars when the latter are rocked.

7. The combination with a sectional rocking-tooth-bar harrow, of a sulky within the harrow, having wheels between the rear tooth-bars of the sections, and bars connecting the harrow and the sulky, the latter moving coincidently with the movement of the tooth-bars.

8. The combination with a sectional rocking-tooth-bar harrow, of a sulky within the harrow, having wheels between the rear tooth-bars of the sections and approximately equidistant therefrom, and bars connecting the harrow and the sulky to maintain the relative 15 position of the wheels and tooth-bars at any 20 position of the latter.

9. The combination with a sectional rock-

ing-tooth-bar harrow, of a sulky within the harrow, having wheels between the rear tooth-bars of the sections and approximately equidistant therefrom, and bars connecting the forward tooth-bars of the harrow and the sulky to move the latter when the tooth-bars are rocked. 25

10. The combination with a sectional rocking-tooth-bar harrow, of a sulky within the harrow, having wheels between the rear tooth-bars of the sections and approximately equidistant therefrom, and bars attached to the sulky and pivotally secured to brackets on the 30 forward tooth-bars of the sections. 35

In testimony whereof I hereunto set my hand, this 21st day of September, 1904, in the presence of two attesting witnesses.

CHARLES S. SHARP.
